James J. Murphy; Max Ciccarelli**CLAIM**

(57) The ornamental design for a solid drawer and drawer frame, as shown and described.

DESCRIPTION

FIG. 1 is a perspective view of a set of solid drawers and the associated drawer frames in an exemplary system shown in broken lines;

FIG. 2 is a perspective view of a selected solid drawer and associated drawer frame shown in FIG. 1;

FIG. 3 is an elevational view of the front of the solid drawer and drawer frame of FIG. 2;

FIG. 4 is an elevational view of a first side of the solid drawer and drawer frame of FIG. 2;

FIG. 5 is an elevational view of a second side of the solid drawer and drawer frame of FIG. 2; and,

FIG. 6 is a top plan view of the solid drawer and drawer frame of FIG. 2.

The broken lines showing is included for the purpose of illustrating environment and forms no part of the claimed design.
